BAFFLE PLATE FOR MUFFLERS

Brewster G. Robbins, Utica, N. Y., assignor to
Herbert S. Powell, Utica, N. Y.

Application February 21, 1938, Serial No. 191,776

2 Claims. (Cl. 181—69)

The present invention relates to new and useful improvements in mufflers for quieting the exhaust of internal combustion engines, and more particularly to improved baffle plates for mufflers, and to an improved method of making such baffle plates.

An object of the invention is to effect a substantial saving of material in making baffle plates for mufflers, and to this end, the invention contemplates the forming of baffle plates from square or substantially square metal blanks.

A further object of the invention is to provide a baffle plate made according to the above method, which will afford a smooth tight fit entirely around the interior surface of the muffler casing, and which will also provide relatively large spaced welding areas around the interior surface of the muffler casing so as to facilitate securing of the baffle plate thereto.

The above and other objects of the invention will in part be obvious, and will be hereinafter more fully pointed out.

In the accompanying drawing:

Figure 1 is a side elevation showing the assembled muffler tubes and baffle plates with a portion of the casing shown in section.

Figure 2 is a fragmentary plan view showing a metal sheet from which the baffle plate blanks are cut.

Figure 3 is a plan view of a substantially square blank from which a baffle plate is formed.

Figure 4 is an end view showing a baffle plate made from the blank of Figure 3.

Figure 5 is a rear view of Figure 4.

Figure 6 is a sectional view taken along the line 6—6 of Figure 4.

Figure 7 is a plan view of a square blank from which a baffle plate may be formed.

Figure 8 is a sectional view through one of the baffle plates made from the blank of Figure 7.

The invention is particularly concerned with the provision of baffle plates for a muffler which is provided with a plurality of expansion chambers. The baffle plates define these expansion chambers, and it is desirable to provide a tight fit between each baffle plate and the interior surface of the muffler casing so that each expansion chamber will be substantially tight. Ordinarily these baffle plates are drawn from a circular blank, and the flange which is formed must be of sufficient width to provide welding areas for securing the baffle plates to the muffler casing. In drawing a circular blank to form a circular baffle plate, the flange of each baffle plate is often wrinkled or buckled due to the crowding of the

metal during the forming operation. Thus, it is difficult to provide a tight connection between such baffle plates and the muffler casing. In order to overcome this difficulty, it has been necessary to use pads to prevent this wrinkling or buckling of the flange. It is, of course, desirable to provide relatively large welding areas on the baffle plates in order to facilitate the securing thereof to the muffler casing. For this reason, it is necessary to provide a relatively wide continuous flange when drawing such baffle plates from circular blanks.

The present invention is concerned with overcoming the above mentioned difficulty, and contemplates the forming of baffle plates from square or substantially square metal blanks. In this manner, there can be provided a relatively narrow smooth flange portion which will provide a substantially tight fit with the interior surface of the muffler casing. Such a baffle plate can be formed by simply using a plunger and a round die without a pad. Because of the fact that the baffle plate is drawn from a square blank, there will be provided relatively large spaced extensions which provide relatively large welding areas for securing the baffle plate to the muffler casing.

Referring more in detail to the accompanying drawing, and particularly to Figure 1, there is shown a muffler assembly with a portion of the muffler casing in section. This assembly includes a muffler casing C and a plurality of tubes 10, 11. There are preferably provided three of these tubes, and the tube 10 extends through an end plate 12 which provides an inlet for the muffler. This tube 10 terminates short of the opposite end plate 13. The tube 11 extends through the end plate 13 and terminates short of the end plate 12, thus providing an outlet for the muffler. The third tube terminates short of both end plates and provides a passage for the gases from the tube 10 to the tube 11. Mounted within the casing C are a plurality of spaced baffle plates 14, through which the tubes extend. The baffle plates are secured to the interior surface of the muffler casing, and are provided with perforations between adjacent baffle plates so as to permit expansion and contraction of the gases of combustion passing through the muffler.

Each of the baffle plates 14, according to the present invention, is made from a square or substantially square metal blank so that a substantial saving of sheet metal results in the cutting of these blanks. As shown in Figure 2, the baffle plates 14 may be formed from a square metal blank S or from a substantially square metal

blank, that is, one wherein the tips T have been cut off. The square metal blank S is shown in Figure 7, and the substantially square metal blank ST is shown in Figure 3.

- 5 In the manufacture of a baffle plate from the substantially square blank ST, shown in Figure 3, a circular die and plunger are employed. The die and plunger are of such diameter that the blank is formed with relatively narrow flange 10 portions 16 which merge into spaced enlarged portions 17. In forming such a blank, there will result a smooth and even flange including the narrow portions 16 immediately adjacent the peripheral edge of the body portion of the formed 15 baffle plate. Any tendency for the metal to crowd or buckle in the region of the narrow portions 16 will be counteracted by the tendency of the metal to "flow" from these portions into the enlarged portions 17. A baffle plate made according to 20 this method assures a smooth and even surface for providing a tight fit with the interior surface of the muffler casing. The enlarged portions 17 are, as illustrated, elongated axially of the muffler casing and provide enlarged areas to facilitate 25 the welding of the baffle plate to the muffler casing.

The body portion of the baffle plate 14 extending across the muffler casing is punched or otherwise cut to provide openings 15 through which 30 the muffler tubes extend.

As shown in Figures 7 and 8, the baffle plate 14a is made from a square blank S. The enlarged portions 17a remain pointed in this form of baffle plate since the tips T of the metal blank 35 are not removed. This baffle plate is also provided with openings 15a through which the muffler tubes extend.

According to the present invention, there is thus provided a baffle plate which is formed from 40 a square or substantially square metal blank. The baffle plate is one which includes at least a narrow portion entirely around the periphery thereof which is smooth so that it will provide a tight fit with the interior of the muffler casing.

45 The relatively narrow flange portions 16, 16a merge into spaced enlarged portions 17, 17a. Thus, there is no buckling or crowding of the metal around the periphery thereof in the region of the reduced flange portions 16, 16a so that a

tight and exact fit is provided with the interior surface of the muffler casing. The axially elongated or enlarged portions 17, 17a serve to strengthen the baffle plate and muffler and also provide enlarged areas for conveniently welding the baffle plates to the muffler casing.

The present invention thus provides a baffle plate for mufflers which is highly efficient, which is strong and durable, and which permits a maximum saving of material during the manufacture thereof. It is to be clearly understood that various changes in the details of construction and arrangement of parts may be made without departing from the scope of the invention as set forth in the appended claims.

I claim:

1. A baffle plate for mufflers, comprising a body portion adapted to extend across the muffler casing and a flange disposed around the peripheral edge of said body portion and extending axially of the muffler casing, said flange affording a continuous smooth tight fit entirely around the interior surface of the muffler casing and including spaced relatively narrow portions tightly fitting against the interior surface of the muffler casing for preventing bending of the baffle plate and also including spaced relatively large portions tightly fitting the interior surface of the muffler casing for providing enlarged areas for welding the baffle plate to the muffler casing.

2. A baffle plate for mufflers, comprising a body portion adapted to extend across the muffler casing and a flange disposed around the peripheral edge of said body portion and extending axially of the muffler casing and at substantially right angles to the body portion, said flange affording a continuous smooth tight fit entirely around the interior surface of the muffler casing and including spaced relatively narrow portions tightly fitting against the interior surface of the muffler casing for preventing bending of the baffle plate and also including spaced relatively large substantially triangular portions tapering away from the narrow portions and said body portion and tightly fitting the interior surface of the muffler casing for providing enlarged areas for welding the baffle plate to the muffler casing.
